UNITED STATES PATENT OFFICE.

PHILIP VIVIANO, OF ST. LOUIS, MISSOURI.

WEIGHING SCALE.

Application filed August 27, 1925, Serial No. 52,806.

This invention relates to an improved weighing scale of the type found more particularly in public places, wherein a coin is frequently used for controlling the same.

In the present invention it is immaterial whether coin control means be utilized, the novelty residing more particularly in the particular shape of the casing, the provision of a rotary calibrated indicator, and novel operating means therefor.

More specifically, it is an object to provide a rotatably mounted disc which is confined in an especially constructed housing, this disc having numbers on its periphery 15 visible through a sight opening to indicate the weight of the occupant of the scale, there being rack and pinion means associated with the central portion of the disc, a depending operating rod, and adjustable 20 weights associated therewith for rendering the structure more or less sensitive, as the case may be.

Other features and advantages of the invention will become apparent from the following description and drawing.

In the accompanying drawing forming a part of this application and in which like numerals are employed to designate like parts throughout the same:

30 Figure 1 is a side view with a portion broken away, and shown in section to disclose the novel features of the invention more plainly.

Figure 2 is a fragmentary sectional and 35 elevational view of the lower portion of the scale showing the relation of parts more particularly.

Referring to the drawings in detail the reference character 1 designates a base from 40 which a standard 2 rises vertically. The reference character 3 indicates a vertically elongated casing or housing, 4 indicates a hollow platform, and 5 a depressible standing plate. The platform is pivoted at 6 to 45 the intermediate portion of the standard and is pressed out to a horizontal position by the coil spring 7. It should be noted that the upper portion of the housing is comparatively narrow in side elevation, while the 50 lower portion is increased in size, considerably as indicated at 7^a. This enlarged portion, provides a substantial ledge at a point intermediate the housing, and this ledge is formed with an elongated sight opening 8, 55 disposed on a plane to allow the occupant of the scale to look down through it and see

a rotary disc 9 on the inside of the housing. This disc is mounted for rotation in any appropriate manner, and is provided on its periphery with graduated scale numbers. 60 Referring now more particularly to Figure 2 it will be seen that the disc is rotated by a pinion 10, fixedly mounted on the shaft thereof, there being a vertical rack bar 11, the teeth of which are in mesh with the teeth 65 of the pinion. Connected to this rack bar is a depending operating rod 12, which extends down into the hollow platform, and is connected with conventional operating means (not shown). Pivoted at 13 on the 70 housing is a rockably mounted arm 14 having a screw threaded end portion upon which a weight 15 is adjustably mounted. Then there is an extension 16 projecting from the point of pivot, this stem being 75 screw threaded to adapt it for reception of the adjustable weight 17. These weighted bars are connected with the central portion of the operating rod 12 through the medium of a link 18.

In operation, it is plain that when the rod 12 is pulled outwardly under the action of the operating means in the hollow platform, it acts on the pinion 10 through the medium of the rack bar 11 to rotate the rotary disc 85 9, and to bring the scale numbers into registry with the sight opening 8, thus indicating the weight of the occupant. The action of parts may be adjusted by proper manipulation and regulation of the weights 90 15 and 17.

It is thought that by considering the description in connection with the drawings, persons familiar with weighing scale structures will be able to obtain a clear understanding of the invention. Therefore, a 95 more lengthy description is thought unnecessary.

While the preferred embodiment of the invention has been shown and described it is 100 to be understood that minor changes coming within the field of invention claimed may be resorted to if desired.

Certain details herein shown are not described and claimed, the same being the subject matter of a divisional application which matured into Patent No. 1,570,872 of January 26, 1926.

Having thus described the invention, what I claim as new is:—

1. In a weighing scale structure, a vertically elongated housing, a base disposed

beneath and connected with said housing, said housing embodying a relatively narrow upper portion, and a widened lower portion, said widened lower portion forming a ledge 5 at the central portion of the housing, and said ledge having a sight opening, a disc rotatably mounted in the housing beneath said ledge, the periphery of the disc being provided with scale numbers visible through 10 said opening, a pinion on the shaft of the disc, a rack bar in operative connection with the pinion, an operating rod connected with the rack bar, a pivotally mounted counterbalancing device embodying screw 15 threaded portions, and weights on the screw threaded portions.

2. In a weighing scale of the class described, a vertically elongated housing, a base disposed beneath and connected with said housing, said housing embodying a 20 relatively narrow upper portion and a comparatively wide lower portion, said widened lower portion forming a ledge at about the center of the housing, and said ledge having a sight opening formed therein, and a graduated scale disk rotatably mounted in the housing and having the graduations thereon located to render them visible through said sight opening. 25

In testimony whereof I affix my signature.

PHILIP VIVIANO.
